LIQUID DISPENSING APPARATUS

Gerald J. Harman, Beverly Hills, Calif., assignor
to Harman Equipment Company, a corporation
of California

Application June 26, 1943, Serial No. 492,435

2 Claims. (Cl. 222—165)

1

My invention relates to apparatus for loading and transporting barrels and dispensing liquid therefrom, of the character embodied in my co-pending application, Serial Number 453,055, filed July 31, 1942, wherein a liquid dispensing apparatus is mounted on a vehicle and provided with a suction manifold having inlet spouts for receiving outlet nozzle of liquid containing barrels, the spouts and nozzle operating when the barrels are moved to a carrying position on the vehicle, to connect the barrels to the suction manifold so that liquid may be withdrawn from the barrels by a pump connected to the suction manifold, and dispensed through hoses connected with the pump.

It is a purpose of my present invention to provide a liquid dispensing apparatus which is characterized by the provision of valves for controlling the withdrawal of liquid from the barrels and the passage of the liquid into the suction manifold, all in a manner to effect communication between the barrels and the manifold when the former are in carrying position on the vehicle, so that upon operation of the pump liquid can be withdrawn from the barrels and into the manifold without leakage of the liquid, and without losing any of the suction created by the pump between the barrels and the suction manifold.

It is also a purpose of my invention to provide in a liquid dispensing apparatus of the above described character, nozzles on the barrels having valves therein, and spouts on the suction manifold likewise having valves therein, and the valves in the spouts and nozzles being normally closed to prevent accidental discharge of liquid from the spouts and nozzles, but manually movable to open positions to place the nozzle in communication with the spouts when the former are inserted into the latter.

A further purpose of my invention is the provision in a liquid dispensing apparatus of the aforesaid character, wherein the valves of the suction manifold although urged to closed position are adapted to be automatically opened when the nozzles are inserted in the spouts, and conversely when the nozzles are removed from the spouts the valves automatically close.

I will describe only two forms of liquid dispensing apparatus, each embodying my invention, and will then point out the novel features thereof in claims.

In the accompanying drawings:

Fig. 1 is a view showing in top plan one form of liquid dispensing apparatus embodying my invention.

2

Fig. 2 is an enlarged vertical sectional view taken on the line 2—2 of Fig. 1.

Fig. 3 is a vertical sectional view taken on the line 3—3 of Fig. 1.

Fig. 4 is a view showing in side elevation and partly in section, another form of liquid dispensing apparatus embodying my invention.

Referring specifically to the drawings and particularly to that form of my invention shown in Figs. 1 to 3, the apparatus is similar to that embodied in my aforesaid copending application in that it comprises a trailer frame F on the rear end of which are a pair of supports S and S¹ for a pair of barrels B and B¹. These supports are secured to cradles C and C¹ (see broken lines Fig. 1), and the cradles are in turn pivoted on the rear portion A of the frame F. Thus the supports S and S¹ are pivoted to occupy a barrel loading position in which they are inclined to the vertical to allow the barrels to be placed thereon, and a barrel carrying position in which they and the barrels are tilted forwardly to the position shown in Fig. 1. As also shown in Fig. 1 shafts T and T¹ are mounted in the frame F and operatively connected to the supports S and S¹ through the link connections disclosed in my copending application hereinbefore referred to, so that by manual operation of cranks K and K¹ the supports can be individually moved to the two positions above described.

Each barrel B or B¹ is provided at its forward end with a discharge nozzle N connected to the barrel by a length of pipe 15, one end of which is threaded into a lateral collar 16 formed on the nozzle. As best shown in Fig. 2, the nozzle N comprises a tubular body 17 the outlet or bottom end of which is normally closed by a valve V seated on the lower edge of a sealing gasket G. This gasket embraces the reduced end portion 18 of the nozzle body, and at its upper end abuts an annular shoulder 19 on the body in order to limit movement of the gasket inwardly on the nozzle.

The gasket G is preferably formed of compressible rubber and is generally of frusto-conical form in section for a major portion of its length, the lower end of the nozzle being tapered as indicated at 20 to accommodate the tapered form of the gasket at that point. The gasket may be formed with an annular flange 21 to facilitate application and removal of the gasket from the nozzle, and also to limit movement of the gasket inwardly of a spout.

The valve V is provided with a stem 22 which extends upwardly through a sleeve 23, secured

axially within the nozzle by a spider 24. The stem 22 extends upwardly through a second sleeve 25, in the upper end of the nozzle body, a sealing ring 26 being carried by the sleeve to produce a fluid-tight seal between the stem and the sleeve. The stem 22 projects from the top of the nozzle body and through a disc 27 secured to the nozzle body top and provided with a pair of ears 28. Within these ears is a pintle 29 on which the hub 30^a of a cam 30 is journaled. Rotatably fitted in the upper end of the stem 22 is a ball bearing 22^a so as to be interposed between the cam 30 and the stem to reduce friction and wear and facilitate rotation of the cam by an operating arm 31. This arm 31 is fixed to the cam at such a point that the cam will remain in either of the two extreme positions to which it is adapted to be rotated as shown by the solid and broken lines in Fig. 3.

An expandible spring 32 surrounds the valve stem 22 at a point between the sleeve 23 and a collar 33, the latter being pinned to the stem. By means of this spring 32 the valve V and valve stem 22 are urged upwardly in the nozzle, the valve abutting the lower edge of the gasket G to close the outlet end of the nozzle, and the upper end of the stem abutting the smallest radius of the cam 30. Thus it will be seen from Fig. 3, that by movement of the arm 31 from the solid line position to the broken line position, the cam will operate to move the stem downwardly against the tension of the spring 32, and thus move the valve V to open position in which it is held by the cam.

As shown in Fig. 1, my liquid dispensing apparatus also includes a hose 34 mounted on a rack 35, supported on a pipe 36, suitably secured to the trailer frame. From this pipe 36 a branch pipe 37 extends to a pump 38 operated by a motor 39, through gears 40. The pump 38 communicates with a suction manifold M through a connection 41.

The manifold M comprises a tubular body 42 arranged horizontally and transversely on the trailer frame, with heads 43 on the opposite ends of the body. Each head is preferably of square form and hollow, as best shown in Fig. 2, and its top is formed with a circular opening to accommodate a valve cage K which depends from the top of the head by the provision of an annular flange 44 bolted to the head. The bottom wall 45 of the cage is of convex form, and at its apex it is provided with a guide sleeve 46 in which the lower end of the stem 47 for a valve V¹ is slidably received. The side wall of the valve cage is provided with a series of openings 48, and spanning these openings is a filtering screen 49, suitably secured to the cage so as to filter oil in its passage from the interior of the cage through the openings and into the manifold.

The upper marginal edge of the cage K is counterbored to provide an annular shoulder 50, against which the lower edge of an annular spout 51 bears. This spout is secured in fixed position on the cage by the provision of an annular flange 52, through which the bolts for securing the flange 44 to the manifold extend. The lower edge of the spout 51 is chamfered to form a seat 53 for the valve V¹, and it is against this seat which the valve is urged by a conical spring 54 interposed between the valve and the bottom wall of the valve cage. Thus it will be seen that the valve is normally closed by the spring to prevent the escape of liquid from the manifold as well as to prevent intake of air.

The inner periphery of the spout 51 is shaped

to provide a conical mouth 55 in which the sealing gasket G is adapted to be received and so as to slightly compress the gasket to have a fluid-tight seal between the spout and the nozzle.

In the operation of the liquid dispensing apparatus just described, each barrel is brought to the horizontal position shown by swinging the respective support S or S¹ to the position shown in Fig. 1, and in this position of the barrel, the nozzle end is extended into the spout 51, the gasket G being interposed between the spout and nozzle to provide the fluid-tight seal before described. The valves V and V¹ being normally closed under the action of their respective springs, once the nozzle is extended into the spout, the valve V may be moved to open position through operation of the cam 30 in the manner previously described. With the opening of this valve it engages the valve V¹ and moves the latter downwardly to open position against the tension of the spring 54. Thus the two valves are now open so that upon operation of the pump 38 suction is produced in the manifold M and, in consequence, in the head 43, to draw oil from the barrel through the nozzle and into the head. From the head the oil passes through the manifold to the pump and from the latter to the hose for dispensing as required.

When liquid is not being dispensed from either barrel, the cam for either valve V may be returned to its normal position to allow the springs 32 to return the valve V to closed position, and likewise to permit the springs 54 to return the valve V¹ to closed position. Thus, should the nozzle N for any reason be removed from the spout 51, liquid cannot accidentally leak from either the nozzle or the spout.

Referring now to Fig. 4, I have here shown another form of liquid dispensing apparatus which is similar to the first apparatus herein described in that it embodies a barrel B on a support S, pivoted on the trailer frame F, and a suction manifold M secured to the frame. The barrel at its forward end is provided with a fitting 56 to which is connected a short length of pipe 57, with the latter connected to an elbow fitting 58, and such fittings and pipe constitute a discharge nozzle N¹ for the barrel. The pipe 57 contains a butterfly valve V² on a stem 59 rotatable in a head 60 by an arm 61 secured to the stem exteriorly of the head and provided with a set screw 62 by which the arm can be secured against rotation to secure the valve in closed position or in any open position of adjustment.

The outlet end of the nozzle is formed interiorly with a spider 63 including a collar 64 in which a pin 65 is screw-threaded. This pin is provided for the purpose of opening a manifold valve, and may be adjusted in the collar to vary the degree of opening of such valve.

The nozzle carries a sealing gasket G¹, similar in construction to the gasket G, and abutting a shoulder 66 on the nozzle to limit its position of adjustment inwardly on the nozzle.

The suction manifold is provided with a head 67 corresponding to one of the heads 43 of the first form of my invention, and in which head is contained a cage K¹ for a valve V³. This cage is of the same construction generally as the cage shown in Fig. 2, and is secured within the head in the same manner. The valve V³ is fixed on the upper end of a stem 68 movable vertically in a sleeve 69 on the bottom wall of the cage K¹. A spring 70 urges the valve to closed position against a seat 71 formed on the inner end of a spout 72.

This spout is provided with a flange 73 by which it is secured to the cage flange, as shown. The upper end of the spout 72 is interiorly tapered to provide a seat 74 which receives and compresses the gasket G¹ to form a fluid-tight connection between the spout and the nozzle.

When the nozzle N¹ is extended to the spout 72, the pin 65 engages the valve V³ to move the latter to open position against the tension of the spring 70, as illustrated in Fig. 4. Thus the nozzle N¹ is placed into communication with the suction manifold head 67 so that by opening the valve V² and setting the pump into the operation, liquid will be drawn from the barrel into the manifold for discharge through the hose as described in 10 connection with the first form of my apparatus. Manifestly, when the nozzle is removed from the spout the pin 65 disengages the valve V³, to allow the spring 70 to return the valve to closed position, and thus the manifold head is sealed against the escape of liquid. Similarly, when the nozzle is removed from the spout the valve V² is manually closed to prevent escape of liquid from the barrel.

Although I have herein shown and described 25 only two forms of liquid dispensing apparatus each embodying my invention, it is to be understood that various changes and modifications may be made therein without departing from the spirit of my invention and the spirit and scope of the 30 appended claims.

I claim:

1. In combination; a barrel; a support for said barrel movable to occupy a loading position and a carrying position; an outlet nozzle on said bar- 35

rel having a first valve therein normally closed; means for urging said valve to closed position; a suction manifold having an inlet spout formed with a seat to receive said nozzle when said support is moved to barrel carrying position; means for sealing the joint between said nozzle and said spout seat; a second valve in said spout; means for urging said second valve to close said spout; and manually operable means on said nozzle for opening said first valve to a position in which it engages and opens said second valve when said nozzle is extended into said spout, whereby said barrel is placed in communication with said manifold to permit liquid in said barrel to be drawn into said manifold.

2. In combination; a barrel having an outlet nozzle; a support for said barrel movable to cause said nozzle to occupy an elevated position and a lowered position; a compressible sealing gasket 20 on and projecting from the free end of said nozzle; a suction manifold beneath said nozzle having an inlet spout provided with a mouth having a seat in which said gasket is received and compressed when said nozzle is moved to lowered position; a first valve at the free end of said nozzle; means for urging said valve against the projecting end of said gasket to close said nozzle; a second valve engageable with said seat for closing the inner end of said spout; means for urging said second valve to closed position; and means for moving said first valve to and holding it in open position wherein it engages and opens said second valve against the action of its urging means.

G. J. HARMAN.
